[57] CLAIM

The ornamental design for a rotisserie counterbalance,
as shown and described.

DESCRIPTION

FIG. 1 is a perspective view of a rotisserie counterbalance,
showing my new design;

FIG. 2 is a perspective view thereof, shown in an alter-
nate position;

FIG. 3 is a side elevational view thereof;

FIG. 4 is a top plan view thereof;

FIG. 5 is a bottom plan view thereof.
